SIDE BEARING FOR RAILROAD-CARS.

1,175,008.

Specification of Letters Patent. Patented Mar. 14, 1916.

Application filed March 15, 1913. Serial No. 754,543.

To all whom it may concern:

Be it known that I, JOHN F. O'CONNOR, a citizen of the United States, residing at Chicago, in the county of Cook and State of Illinois, have invented a certain new and useful Improvement in Side Bearings for Railroad-Cars, of which the following is a full, clear, concise, and exact description, reference being had to the accompanying drawings, forming a part of this specification.

My invention relates to improvements in side bearings for railroad cars.

The object of my invention is to provide side bearings adapted to operate efficiently when the railroad car to which the same are applied is traveling either upon a straight or upon a curved track.

In the accompanying drawings forming a part of this specification Figure 1 is an end view of side bearings shown in place between the upper and lower bolsters of a railway car. Fig. 2 is an elevation. Fig. 3 is a detail view of the upper and lower bearings. Fig. 4 is a detail showing in plan view the upper bearing.

In the drawings 5 represents a body bolster of a railway car, 6 the truck bolster, 7 the upper side bearing suitably secured to the body bolster, 8 the lower side bearing suitably secured to the truck bolster. It will be understood that these side bearings may be reversed, the upper side bearing applied to the truck bolster and the bearing herein designated as the lower side bearing applied to the body bolster. The lower side bearing comprises an antifriction roller 9 and an adjustable cradle 10 in which the said antifriction roller is journaled, 11 a cradle clamp in which the adjustable cradle is pivoted on an axis transverse to the axis of the antifriction roller 9 by means of trunnions 12 at either side of the said adjustable cradle. The cradle clamp 11 is suitably secured to the upper face 13 of the truck bolster 6, preferably by rivets 14, 14 passing through flanges 15, 15 along either side of said cradle clamp and through the top member of the truck bolster 6. The construction of the lower bearing is well known, and needs no further description.

The upper bearing member 7 is of novel construction, and it is in features of this member hereinafter described that my invention consists. The upper bearing comprises a member 16 disposed transversely of the length of the body bolster 5 and above the lower bearing 8, the said member having a bearing face 17, which preferably is detachably secured to the member 16 by a suitable means, preferably the rivets 18, 18, which member 17 engages angular shoulders, 19, 19 at either end of the member 16. The member 16 is suitably secured to the body bolster 5, preferably by means of rivets 20, 20 passed through the said bolster, and flanges 21, 21 with which the said member 16 is laterally provided. The bearing face of said upper bearing member is lowest at the points substantially above the central portion or antifriction roller of the lower bearing when the body bolster and truck bolster of the car to which the bearings are applied are in normal position, parallel to each other, and from said point the bearing surface extends upwardly toward either end.

It is well understood that in curves in railroad tracks the outer rail of the curved track is higher than the inner rail. It is because of this condition and other conditions in the practical operation of railroads hereinafter referred to that my invention is of great utility.

When railroad cars are being operated upon a straight track it is desirable that a comparatively slight clearance be had between the upper and lower side bearings so as to prevent lateral sway of the car bodies in reference to the car trucks. When a railroad car enters a curve in the track the outer rail being higher than the inner rail the truck first entering the curve not only curves with the track, but the said truck tips in relation to the other truck of the car before the other or rear truck enters the curve. When the front truck of a car enters the curve the outer end of the truck bolster that is the end of the truck bolster at the other side of a curved track moves forwardly from the end of the body bolster, that is the end of the truck bolster at the inner side of the curved track and similarly the inner end of

the truck bolster moves rearwardly from the inner end of the body bolster, that is the end of the body bolster at the inner side of the curved track, the said bolster turning about 5 the king pin or center bearing. Meanwhile the outer end of the truck and truck bolster moves upwardly in its travel in relation to the inner end of the truck and truck bolster, and thus in side bearings heretofore em- 10 ployed where a small clearance space, as is desirable, is provided between the upper and lower members of the bearing when the car is upon a straight track, the lower bearings at the outer end of the truck bolster when 15 entering a curve lift against the upper bearing member. This is particularly true in cars having a rigid underframe and in which consequently there is little weaving of the car body. The result often times is to 20 separate the two bolsters at their central bearing point, and particularly in the case of stiff car bodies, such as those in refrigerator cars, the truck is disconnected from the car body, resulting in damage to the car, or 25 the wrecking of the same, or the train of which the car is a part. Often times the wheels of the truck become derailed, and generally in a direction toward the outside of the curve of the track. My invention 30 overcomes this difficulty, as will appear from the following description of the operation of my device.

When the car upon which my device is applied is entering a curve in the track 35 upon which it is being operated the outer wheels of the front truck, that is, on that side of the truck adjacent the outer side of the curve in the track, ride relatively higher than the wheels of the front truck 40 at the inner side of the turn on account of the increased height of the outer rail of the track over the inner rail thereof. As the outer wheels of the front truck are lifted the truck bolster of the said truck 45 is also lifted at its outer end, that is, the end adjacent the outer side of the curved track. The rear truck of the car before entering the curve in the track is level, the body bolster and truck bolster at the rear 50 end of the car being substantially parallel, and consequently in cars having rigid underframes the body bolster at the forward end of the car does not substantially change its relative horizontal position while the 55 front truck is entering the curve. Consequently as the outer end of the front truck bolster is lifted the outer end of the truck bolster approaches the outer end of the front body bolster, and relatively the inner end of the truck bolster separates 60 from the inner end of the body bolster at the front end of the car. Meanwhile the front body and truck bolsters move relatively upon their point of pivotal connec-

tion at the king pin and center bearing in 65 the manner hereinbefore described.

In my side bearing the bearing faces of the upper bearing member recede upwardly from a point substantially at the longitudinal center thereof at an angle sufficiently acute to permit the lower bearing member associated with the front bolster at the outer end thereof to clear the upper bearing member associated with the outer end of the body bolster at the front end 70 of the car as the front truck bolster at its outer end moves forwardly relatively to the front body bolster at its outer end, and while the outer ends of the front bolsters of the car approach each other vertically 75 while the front truck of the car is entering the curve. Meanwhile the clearance between the bearing members attached to the inner ends of the front bolsters of the car are vertically separated. Thus by reason of my device in providing for a clearance, which is substantially constant between the outer bearing members of the front bolsters of the car, the difficulties hereinbefore mentioned are obviated, and at the same time the clearance between these side bearings in all relative positions of the trucks to the car body is maintained 80 at a minimum to prevent undue side swaying of the car.

95 I claim:—

1. In a side bearing for railway cars, the combination with the body and truck bolsters, of two bearing members attached to said bolsters, one of said members having bearing surfaces inclined from the horizontal from a line extending substantially radially from the pivotal connection between the bolsters, and the other member having substantially a line bearing surface which extends substantially parallel to the center line of the bolster by which it is carried whereby, as the truck bolster is turned and raised relatively to the body bolster, the clearance between the two bearing members remains always substantially the same.

100 2. In a side bearing for railway cars, the combination with pivoted body and truck bolsters, of a bearing member carried by the under side of the body bolster, said bearing member having flat bearing surfaces inclined upwardly from the center 105 thereof on opposite sides, and a bearing member carried by the top side of the truck bolster, said last named bearing member having a substantially fixed line bearing whereby, as the bolsters are turned angularly relatively to each other and the end 110 of the truck bolster is raised vertically toward the body bolster when the truck 115 strikes a curve, the space between the bearing surfaces remains substantially constant.

3. A roller side bearing for railway cars which comprises in combination with the body and truck bolsters, a bearing member having bearing surfaces inclined upwardly from the central portion thereof away from a horizontal plane, and another bearing member having a roller the axis of

which extends substantially parallel with the center line of the bolster by which it is carried.

JOHN F. O'CONNOR.
